PONTOON BRIDGE SUPPORT

John W. Beretta, San Antonio, Tex.

Application September 24, 1946, Serial No. 699,070

15 Claims. (Cl. 14—27)

(Granted under the act of March 3, 1883, as
amended April 30, 1928; 370 O. G. 757)

1

The invention described herein may be manufactured and used by or for the Government for governmental purposes, without payment to me of any royalty thereon.

This invention relates to bridges, more particularly it is directed to the shore connection of a floating bridge structure.

In floating bridges, particularly those of a military nature, it has been customary to connect the floating section of the bridge with the bank by a short connection consisting of trestle-supported sections, the number of sections being dependent upon the depth of water and other inshore conditions. The trestle next to the inshore boat of the floating section is connected to the floating section by a hinge span, and like the other trestles, consists of a transom fixedly connected to columns supported by mud shores or the like. This type of connection is satisfactory in a low capacity bridge having a flooring system of the balk and chess type but has the weakness that the entire load coming onto the floating section is thrown on the end span of that section as a concentrated load with the result that it is difficult to get enough floating support under that portion of the bridge. In a new type of high capacity floating bridge now coming into use a flooring system of hollow beams is used in lieu of the earlier balk and chess decking and the difficulties inherent in the hinge span connection of the earlier bridge referred to above are avoided by projecting the beams beyond the inshore boat to the first transom of the shore connection. It has been found, however, that when a heavy load passes over the bridge the beams in the span between inshore boat and its adjacent transom are overstressed due to the fact that the transom is relatively fixed while the inshore boats sink deeper into the water as the load passes over them. With this in mind, and in accordance with a feature of my invention, means are provided for permitting heightwise movement of the flooring at the transom support concomitantly with the heightwise movement of the adjacent inshore boats. As illustrated, this means consists of a transom fixedly connected to supporting columns, a floor supporting member located above the transom and yieldable means interconnecting the transom and supporting member arranged to permit heightwise movement of the floor supporting member as the load passes over it.

A further object of the invention is to provide a floating bridge structure including yielding supports at the end of the floating portion of the pontoon bridge, using trestle supports, which will

2

enable the use of a continuous span of bridge flooring between the last ponton and the first trestle support.

Another object of the invention is to provide a yielding support for a ponton bridge which may be incorporated on top of the transom of a trestle support adjoining each of the ends of the bridge.

Another object of the invention is to provide a toggle spring or yielding support for a ponton bridge, which will enable the extension of continuous balk or flooring of the floating portion of the bridge from the last ponton to the first trestle transom at each end of the bridge, by yielding vertically and thus reducing the slope of the roadway and thereby preventing the overstressing of the balk in the last span and also providing the necessary articulation between the continuous ponton end span of balk and the first trestle span of balk.

20 With the above and other objects and advantages in view the invention consists of certain features of construction and operation of parts, which will hereinafter be described and shown in the accompanying drawings, in which:

25 Fig. 1 is a side elevation of the invention applied between a transom adjustably mounted on columns at one end of the floating portion of a ponton bridge and a load carrying bridge floor-supporting beam mounted for up and down movement on the columns, with bumper carrying brackets adjustably mounted on the columns for limiting the downward movement of the floor-supporting beam and means for limiting the upward movement thereof;

30 Fig. 2 is a longitudinal sectional view taken on line II—II of Fig. 1;

35 Fig. 3 is an enlarged fragmentary side elevation of the left end portion of Fig. 1 and illustrating the invention in full lines and other parts of 40 the supporting trestle of the ponton bridge in broken lines;

45 Fig. 4 is a vertical sectional view taken on line IV—IV of Fig. 1;

Fig. 5 is another vertical sectional view taken on line V—V of Fig. 1;

50 Fig. 6 is an enlarged detail vertical sectional view through a bottom roller, track and connected parts used in carrying out the invention;

Fig. 7 is an enlarged side elevation of a bumper carrying bracket for limiting the downward movement of the bridge floor-supporting beam on a column;

55 Fig. 8 is another side elevation of the bumper carrying bracket;

Fig. 9 is a top plan view thereof;

Fig. 10 is a fragmentary detail view of the lower end of the bumper carrying bracket;

Fig. 11 is an enlarged vertical sectional detail view taken on line XI—XI of Fig. 3;

Fig. 12 is an enlarged vertical sectional detail view taken on line XII—XII of Fig. 1;

Fig. 13 is a diagrammatic view illustrating the invention applied on one end of a ponton bridge at the point where the floating portion of the bridge connects to a fixed portion or approach near the river bank.

Fig. 14 is a schematic view showing a typical floating bridge section and trestle supported shore connection.

Referring to the drawings, the improved transom assembly is designated generally by A and is adapted for use on one or more of the trestles at each end of the bridge. The transom assembly consists broadly of a lower beam or transom, an upper floor supporting beam and a yielding support interposed between the upper and lower beams. For purpose of illustration only one transom assembly will be shown in detail and described.

The yielding support or toggle spring device is incorporated on top of a lower beam 1, Fig. 1, mounted on top of a standard type of transom 2 by means of adapters 3. The transom 2 is adjustably supported on vertical columns 4 of a trestle 5 adjoining the end of the floating portion 6 of the ponton bridge 7, Fig. 13. The height of the transom 2 on the vertical column 4 may be adjusted to meet changes of water level, or otherwise to alter the elevation of the trestle bridge floor, by means of chain hoists, for example, or similar devices well known in the art, attached to the tops of columns 4 and to the ends of the transom 2. Typical hoisting means are described at pages 5 to 9 of War Department Technical Manual TM5-276, October 19, 1943, entitled "Ten-ton trestle bridge." The yielding support includes an upper transversely extending supporting beam 8 movably mounted on the columns 4 by means of guide brackets 9 on its ends and having a balk adapter 10 having longitudinal balk or floor members 11 mounted thereon. The balk adapter 10 consists of dual swivel pipes 12, Figs. 4 and 5, which extend transversely in spaced parallel relation on the supporting beam 8 and are held in their spaced relation by means of suitably spaced tie angle members 13. The swivel pipes 12 are provided with collars 14 at their ends and have a plurality of bearings 15 arranged in spaced relation thereon, which bearings 15 are provided with the tie angle members 13 which are welded or otherwise connected to the upper surface of the supporting beam 8.

Interposed between the lower beam 1 and the upper supporting beam 8 is a transversely extending and contracting mechanism or spring operated toggle indicated generally by B of the yielding support and consists of a suitable number of intermediate diagonal pivot arms or levers 17, 17' and 17'' of equal lengths and formed into pairs providing lazy tongs with the pairs of intermediate levers crossing each other at their medial points and pivotally connected in spaced relation at these points by intermediate pivot pins 18 illustrated in detail in Fig. 11. One of each pair of the end link arms 19 and 19' of the lazy tongs at one of their ends are pivoted in spaced relation by means of end pivot pins 20 illustrated in detail, Fig. 12. The intermediate pivot pins 18 extend transversely with respect to the upper and lower beams 1 and 8 respectively, with the

end pivot pins 20 extending parallel to and in the same plane as the intermediate pivot pins 18.

The upper ends of the intermediate link arms 17'' are pivotally connected in spaced relation by a pivot pin 21 to a bracket 22 mounted on the lower side and at the middle of the upper beam 8 and the lower ends of the levers 17' are pivotally connected in spaced relation by a pivot pin 23 to a bracket 24 mounted on the upper side and at the middle of the lower beam 1 of transom 2, Figs. 1 and 4, each of the pivot pins 18 forming the fulcrum for each pair of crossed levers. The lower ends of the levers 17, 17' and 19 have lower rollers 25 mounted thereon, which engage in tracks 26 mounted on the upper side and extending longitudinally of the lower beam 1 and the upper ends of levers 17, 17' and end levers 19' have upper rollers 27 provided thereon, which engage in tracks 28 mounted on the lower side of and extending longitudinally of the upper beam 8, Figs. 1 and 5. The rollers 27 engaging the upper tracks 28 are mounted on the upper ends of the link arms in the same manner as the rollers 25 on the lower ends of the link arms engaging the lower tracks 26 as shown in enlarged detail of a roller 25 on the lower track, Fig. 6, wherein the ends of a roller shaft 29 are reduced in diameter and threaded for receiving nuts 30 which retain the lower ends of the link arms on the roller shaft 29.

The intermediate and end pivot pins 18 and 20, respectively, are elongated for connecting tension springs 31 thereto at each end thereof, which tension springs 31 extend in horizontal alignment on opposite sides of the levers of the lazy tong system. Referring to Fig. 11, which shows a detail view of one of the intermediate pivot pins 18 and connected parts, certain ends of the levers 17 are pivotally mounted on reduced end portions 32 of the pin on opposite sides of an enlarged middle portion 33 thereof and sleeves 34 are threadably mounted on the reduced end portions 32 to hold the ends of levers 17 in proper position thereon and are locked in their adjusted position by set screws 35. Adjacent to the outer ends of the sleeves are collars 36, each having one end of each of two tension springs 31 connected thereto, which are held in separated relation by means of rings 37 mounted on the collars intermediate the ends thereof, and on the outer ends of the sleeves are plates 38 for holding one end of a spring on the collars 36. The end pivot pins 20 are identical with the intermediate pivot pins 18 except that the sleeves 34' on the reduced end portions 32' extending from the intermediate enlarged portion 33' thereof as shown in detail in Fig. 12 are shorter in length than the sleeves 34 of the intermediate pivot pins 18, also the collars 36' on the end pivot pins 20 are shorter in length than the collars 36 on the intermediate pivot pins 18 and there are no rings on the collars 36 because each collar 36 has only one end of a tension spring 31 connected thereto, with the plates 38' mounted on the ends of the sleeves 34' holding the ends of the tension springs on the collars.

The columns 4 are provided with bumper members indicated generally by C as more particularly illustrated in enlarged detail in Figs. 7 to 10 inclusive. Each of the bumper members C consists of a bracket 39 adjustably mounted on a column 4 and having clamping members 40 hinged by pins 41 between two hinged plates 42 on the upper and lower ends of the bracket, with the free ends of the clamping members being threaded and engaging in keeper members 43,

where the free ends of the clamping members are detachably held by means of nuts 44 mounted on the threaded ends of the clamping members. In Fig. 10, which shows a fragmentary lower end of the bracket, the clamping member 40 is removed from the hinge plates 42. A chain 45 is connected at one end to the upper end and on the outer side of the bracket 39 and has a pin 46 connected at its other end, which is adapted to be placed through a vertically extending slot 47 formed in the bracket 39 and to enter suitably spaced vertically arranged holes 48, Fig 1, provided in the columns 4 for adjusting the bumper bracket 39 on the columns. On the inner side of the bracket 39 is a reinforcing rib 49 having a bumper block 50 suitably mounted on the upper end thereof. A bumper block 51 is mounted on the bottom of, and at each end of the upper beam 8, Figs. 1 and 2, which bumper blocks 51 are positioned above the bumper blocks 50 on the upper ends of the reinforcing ribs 49 of the brackets 39. Chains 52 are each connected at one end to a lift pin 53 adapted to be inserted through apertures formed in angle clips 54 mounted on the bottom of and adjacent to the ends of the upper beam 8. The other ends of chains 52 are connected to pins 55 on angle clips 56 mounted on the bottom beam 1 at its ends.

In the construction of the bridge support, the balk or longitudinal floor members 11 of the pontoon bridge are connected to the balk adapter 10 which provides not only the balk connectors, but also the necessary articulation as the support yields vertically under the passage of vehicles or other loads such as troops. The load is carried onto the supporting beam 8, which distributes the vertical reaction to upper interconnecting points of the link arms of the toggles, the center ones 17' of which are fixed by a pin 21 to the bracket 22 on the supporting beam 8, while the other upper interconnecting points of the toggles are free to move against the action of springs 31 laterally in opposite directions on the upper rollers 27 as the support yields vertically. The horizontal components of the several vertical load reactions are carried from the diagonal toggle members through the pivot pins 18 and 20 to the horizontally arranged tension springs 31 which provide yielding resistance to the load reaction. The vertical components of the several load reactions are carried by the lower interconnecting points of the link arms of the toggles, the center ones 17' of which are fixed by a pin 23 to the bracket 24 on the lower beam 1, while the other lower interconnecting points of the toggles are free to move against the action of the springs 31 laterally in opposite directions on the lower rollers 25 from the pin 23. The load reactions are transmitted from the lower beam 1 to the transom 2 through the transom adapters 3. The yielding support is limited in its vertical upward movement by means of the restraining chains 52 and in its downward movement by means of the bumper members 50 and 51.

It will thus be seen that this invention provides a novel and efficient form of yielding support for the shore connection of pontoon bridges which is well adapted for the purpose intended. Even though there has herein been shown and described the invention as comprising certain features of construction and operation of parts, it is nevertheless to be understood that various changes may be made therein, if the changes do not depart from the spirit or scope of the claims.

Having thus described my invention, what I

claim as new and wish to secure by Letters Patent is:

1. A floating bridge structure comprising in combination, a fixedly supported lower beam, an upper beam adapted to support a load and mounted to move vertically relative to said lower beam, a yielding support connecting said lower beam with said upper beam, said yielding support comprising a lazy tong lever system laterally expandable relative to said structure comprising a series of diagonal levers pivoted together intermediate their lengths and at their ends, the center pivots thereof being joined to each other by tensional springs resisting lateral expansion of said system, the knuckles formed by the end pivots of one side of said system being adapted to sustain said upper beam and the knuckles formed by the end pivots of the opposite side being adapted to be sustained by said lower beam, for permitting vertical movement of said upper beam relative to said lower beam upon a load being applied to said upper beam, flexible restraining members connected to said upper and lower beams for limiting the upward vertical movement of said upper beam and means for limiting the vertical downward movement of said upper beam.
2. A floating bridge structure comprising in combination, columns, a lower beam fixedly supported on said columns, an upper beam adapted to support a load and mounted to move vertically on said columns relative to said lower beam, a yielding support connecting said lower beam with said upper beam, said yielding support comprising a lazy tong lever system laterally expandable relative to said structure comprising a series of diagonal levers pivoted together intermediate their lengths and at their ends, the center pivots thereof being joined to each other by tensional springs resisting lateral expansion of said system, the knuckles formed by the end pivots of one side of said system being adapted to sustain said upper beam and the knuckles formed by the end pivots of the opposite side being adapted to be sustained by said lower beam, for permitting vertical movement of said upper beam relative to said lower beam upon a load being applied to said upper beam, chains connected to said upper and lower beams for limiting the upward vertical movement of said upper beams and bumpers mounted on said columns and upper beam for limiting the downward movement of said upper beam.

3. A floating bridge structure comprising columns, a transom secured to said columns, a fixed bridge portion, a floating bridge portion connected to said fixed bridge portion above said transom and a yielding support mounted on said transom at the connecting point of said floating bridge portion and said fixed bridge portion, said yielding support including a lower beam mounted on said transom, an upper beam adapted to support a load and mounted to move vertically on said columns relative to said lower beam, an expanding and contracting mechanism arranged between said upper and lower beams, said expanding and contracting mechanism including a series of levers having upper and lower ends pivoted together and formed into pairs, said pairs of levers crossing each other at their medial points, pivot pins connecting said pins of said levers together in spaced relation at their medial points and pivot pins connecting one of the ends of each pair of end levers together in spaced relation, said upper ends of the middle levers pivoted to

said upper beam and said lower ends of other middle levers pivoted to said lower beam, rollers carried on the other upper ends of said levers and engaging said upper beam, rollers carried on the other lower ends of said levers and engaging said lower beam and horizontally aligned tension springs connecting said pivot pins together, said roller carrying upper and lower ends of said levers adapted to move against the action of said springs laterally on said rollers from said pivoted connected upper and lower ends of said middle levers under said upper beam and on said lower beam as said upper beam yields vertically under a load.

4. A yielding support for a floating bridge comprising in combination, a fixedly supported base, an upper beam thereabove adapted to support an eccentric and variable load and mounted to move vertically relative to said base while remaining parallel thereto, a lazy tong lever system laterally expandable relative to said base and beam and interposed between the same, said system comprising a series of diagonal levers pivoted together at their middles and at their ends, the center pivots thereof being joined together by tensional springs resisting lateral expansion of the system, the knuckles formed by the upper end pivots of said system sustaining said loaded beam and the knuckles formed by the lower end pivots being sustained by said base, each of one pair of opposite knuckles being pivotally connected to said base and said beam respectively and the remaining upper and lower knuckles carrying bearing means adapted to bear against said base and beam respectively, and cooperating guide means carried by the base and beam for maintaining said base and beam in vertical alignment.

5. A yielding support for a floating bridge comprising in combination, a fixedly supported base, an upper beam thereabove adapted to support an eccentric and variable load and mounted to move vertically relative to said base while remaining parallel thereto, a lazy tong lever system laterally expandable relative to said base and beam and interposed between the same, said system comprising a series of diagonal levers pivoted together at their middles and at their ends, the center pivots thereof being joined together by tensional springs resisting lateral expansion of the system, the knuckles formed by the upper end pivots of said system sustaining said loaded beam and the knuckles formed by the lower end pivots being sustained by said base, each of one pair of opposite knuckles being pivotally connected to said base and said beam respectively and the remaining upper and lower knuckles carrying rollers adapted to bear against said base and beam respectively, tracks mounted on said base and beam engaging said rollers when the latter move laterally as said beam yields vertically under a load, cooperating guide means carried by the base and the beam for maintaining said base and beam in vertical alignment, bumpers carried by the guide means to limit downward movement of said beam, and flexible connections between said base and beam to limit upward movement of the latter.

6. A ponton bridge structure comprising in combination, supporting columns, a transom fixedly supported thereon, an upper beam above said transom adapted to support a load and mounted to move vertically on said columns relative to said transom, a balk adapter mounted on said upper beam for supporting longitudinal

flooring of a continuous ponton end span and first trestle span of the bridge, a lazy tong lever system laterally expandable relative to said bridge structure and interposed between said transom and said upper beam, said system comprising a series of diagonal levers pivoted together intermediate their lengths and at their ends, the center pivots thereof being joined together by tensional springs resisting lateral expansion of the system, the knuckles formed by the upper end pivots of said system being adapted to sustain said upper beam and the knuckles formed by the lower end pivots being adapted to be sustained by said transom, each of one pair of opposite knuckles being pivotally connected to said transom and said beam respectively, and means on said balk adapter for connecting the longitudinal flooring thereto and providing articulation between the continuous end span and the first trestle span of the bridge.

7. A yielding support for a floating bridge comprising in combination, a transom fixedly supported by vertical columns, an upper beam slidably mounted on said columns above said transom and adapted to support an eccentric and varying load, a lazy tong lever system laterally expandable relative to said transom and beam and interposed between the same, said system comprising a series of diagonal levers pivoted together intermediate their lengths and at their ends, the center pivots thereof being joined together by tensional springs resisting lateral expansion of the system, the knuckles formed by the upper end pivots of said system being adapted to sustain said movable beam and the knuckles formed by the lower end pivots being adapted to be sustained by said transom, each of one pair of opposite knuckles being pivotally connected to said transom and said beam respectively and the remaining upper and lower knuckles carrying bearing means adapted to bear against said transom and beam respectively, tracks mounted on said transom and beam engaging said bearing means as the latter move laterally when said beam yields vertically under a load, and means to limit both downward and upward movement of said beam.

8. Resilient supporting structure for supporting and transmitting variable loads, which comprises, in combination, a movable load supporting member and a stationary base member, and resilient means interposed between and connected to the load supporting member and to the base member and maintaining these members substantially parallel, the said resilient means comprising a lazy tong lever system yieldable under variable loads applied to any portion of the movable load supporting member for enabling movement of the load supporting member towards the base member under the force of a load applied thereto, the lazy tong lever system including a series of diagonal levers centrally pivoted together at their ends, and tensional springs interconnecting the center pivots of the levers and resisting lateral expansion of the said levers, the end pivots of one side of the lever system contacting the movable load supporting member and defining knuckles adapted to sustain the said movable load supporting member, the end pivots of the opposite side of the lever system contacting the base member and being sustained by the said base member.

9. A load supporting and transmitting structure, which comprises a movable load supporting member and a stationary base member towards which the movable load supporting member is

moved by the force of a variable load applied to any portion of the surface thereof, a lazy tong lever system interconnecting the load supporting member and the base member, the said lazy tong lever system including a series of laterally expandable diagonal levers pivoted together centrally and at their ends, tensional springs interconnecting the center pivots of the levers and resisting lateral expansion of the lever system, the end pivots of one side of the lever system forming pivotal connecting knuckles with the movable load supporting member which knuckles sustain the said load supporting member, end pivots of the opposite side of the lever system forming pivotal connecting knuckles with the base member and being sustained by the base member, and guide instrumentalities interconnecting the movable load carrying member and the base member and including upright guide means mounted on the base member and guide brackets mounted on the load carrying member extending around the upright guide means for maintaining the load carrying member and base member in alignment.

10. A load supporting and transmitting structure which comprises, in combination, a movable load supporting member and a stationary base towards which the movable load supporting member is moved by the force of a variable load applied to any portion of the surface thereof, a lazy tong lever system interconnecting the load supporting member and the base member, the lever system including a series of laterally expandable diagonal levers pivotally connected together centrally and at their ends, tensional springs interconnecting the center pivots of the levers and resisting the lateral expansion of the said system, the end pivots of one side of the lever system forming pivotal connecting knuckles with the movable load supporting member, which knuckles sustain the load supporting member, end pivots of the opposite side of the lever system forming pivotal connecting knuckles with the base member and being sustained by the base member, guide instrumentalities interconnecting the movable load carrying member and including vertically disposed guide-standard means mounted on the base member and guide brackets mounted on the load carrying member and extending around the vertically disposed guide-standard means for maintaining the load carrying member and base member in alignment, and bumper means carried by the vertically disposed guide-standard means for limiting motion of the load carrying member toward the said base member.

11. A load supporting and transmitting structure which comprises, in combination, a movable load carrying member and a stationary base member towards which the movable load carrying member is moved by the force of a variable load applied to any portion of the surface thereof, a lazy tong lever system interconnecting the load carrying member and the base member, the lazy tong lever system including a series of laterally expandable diagonal levers pivotally connected centrally thereof and at their ends, torsional springs interconnecting the center pivots of the lever and resisting the lateral expansion of the said system, the end pivots of one side of the lever system forming pivotal connecting knuckles with the movable load carrying member, which knuckles sustain the load carrying member, end pivots of the opposite side of the lever system forming pivotal connecting knuckles with the base member and being sustained by the base member 75

member, guide instrumentalities interconnecting the movable load carrying member and the base member and including vertically disposed guide standard means, and guide brackets mounted on the load carrying member extending around the vertically disposed guide standard means for maintaining the load carrying member and the base member in alignment, bumper means mounted on the said guide standard means for limiting motion of the load carrying member towards the base member, and flexible restraining means interconnecting the load carrying member and the base member for limiting motion of the load carrying member.

15 12. A load supporting and transmitting structure which comprises, in combination, a movable load carrying member and a stationary base member towards which the movable load carrying member is moved by the force of a variable load applied to any portion of the surface thereof, a lazy tong lever system interconnecting the load carrying member and the base member, the lever system including a series of laterally expandable diagonal levers pivotally connected centrally thereof and at their ends, torsional springs interconnecting the center pivots of the levers and resisting the lateral expansion of the said system, end pivots of one side of the lever system forming pivotal connecting knuckles with the movable load carrying member, which knuckles sustain the load carrying member, end pivots of the opposite side of the lever system forming pivotal connecting knuckles with the base member and being sustained by the base member, cooperating guide instrumentalities interconnecting the movable load carrying member and the base member for maintaining the load carrying member and the base member in alignment, means carried by the base member for limiting movement of the load carrying member toward the base member, and flexible means interconnecting the load carrying member and the base member for limiting movement of the load carrying member away from the base member.

30 13. A load supporting and transmitting structure which comprises, in combination, a movable load carrying beam, and a stationary base member towards which the beam is moved by the force of a variable load applied to any portion thereof, a lazy tong lever system interconnecting the beam and base member, the lever system including a series of laterally expandable diagonal levers pivotally connected centrally thereof and at their ends, torsional springs interconnecting the center pivots of the levers and resisting the lateral expansion of the lever system, end pivots of one side of the lever system forming pivotal connecting knuckles with the said beam, which knuckles sustain the beam, end pivots of the opposite side of the lever system forming pivotal connecting knuckles with the base member and being sustained by the base member, bearing means carried by end pivotal connections of diagonal levers intermediate the end levers of the system, certain of the bearing means bearing against and supporting the said beam and others of the said bearing means bearing against and being supported by the said base member, guide means carried by the base member and the beam and cooperating to maintain the said beam and base member in vertical alignment, means carried by the base member for limiting downward movement of the beam, and flexible means interconnecting the beam and base member for limiting upward movement of the beam.

45 50 55 60 65 70

11

14. A load supporting and transmitting structure comprising a movable load carrying member and a relatively stationary base toward which the load carrying member is moved by the force of a variable load applied to any portion of the surface thereof, and a lazy tong lever system interconnecting the load carrying member and the base and including a plurality of diagonal levers pivotally interconnected at their centers and ends, and being laterally expandable, and 10 tensional springs interconnected at the center pivots of the levers and resisting lateral expansion of the said levers, end pivots of one side of the lever system forming sustaining knuckles engaging the movable load carrying member for sustaining the same, end pivots of the opposite side of the lever system engaging the base and being sustained by the said base.

15. A load supporting and transmitting structure comprising a movable load carrying member and a stationary base towards which the load carrying member is moved by the force of a variable load applied to any portion of the surface of the load carrying member, a lazy tong lever system engaging the load carrying member and the stationary base and comprising a series of 20 diagonal levers pivoted together centrally and at their ends, tensional springs interconnecting the center pivots of the lever system and resisting
